UNITED STATES PATENT OFFICE.

FRED M. HARE, OF KIEFER, OKLAHOMA.

SAND-SHIELD FOR OIL-WELLS.

1,389,550.

Specification of Letters Patent. Patented Aug. 30, 1921.

Application filed December 14, 1920. Serial No. 430,687.

To all whom it may concern:

Be it known that I, FRED M. HARE, a citizen of the United States, residing at Kiefer, in the county of Creek and State of Oklahoma, have invented new and useful Improvements in Sand-Shields for Oil-WellS, of which the following is a specification.

The object of my present invention is the provision of a shield for oil wells, calculated 10 to effectively protect the cups and valves of the well tubing against sand.

To the attainment of the foregoing, the invention consists in the improvement as herein-after described and definitely claimed.

15 In the accompanying drawings, forming part hereof:

Figure 1 is a view illustrating my novel shield as properly arranged relatively to well tubing.

20 Fig. 2 is a horizontal section, on a large scale, taken in the plane indicated by the line 2—2 of Fig. 1.

Similar numerals of reference designate 25 corresponding parts in both views of the drawings.

My novel shield 1 is applied on what is generally designated the anchor section 2 of well tubing; the said anchor section 2 being provided at 3 with one or more apertures.

30 The shield is preferably formed of metal in general tubular form, is open at its lower end as indicated by 4, is provided about the proportional distance illustrated above the end 4 with an aperture 5, and is also provided with an upper reduced end portion 6 which receives and is connected by a thread 6^a to the anchor section 2 and is calculated to maintain the major portion of the side wall of the shield 1 in spaced relation to the 40 anchor section 2 so that a space about the

anchor section 2 is afforded within the major portion of the shield from a point above the opening or openings 3 to the lower end of the shield 1.

The practical advantage of my novel 45 shield will be fully appreciated when it is stated that the aperture 5 is intended to limit the level of the fluid in the well for the purpose of keeping the floating sand from getting low enough to enter the shield 1 at 50 the lower end 4 thereof; the said end 4 being open and sufficiently large to render the suction so light that it will not lift the sand. Therefore when the well is filled with sand up to the open end 4 of the shield 1 it will 55 make its presence known whereupon the difficulty may be overcome by raising the tubing so that the shield 1 will rest a few feet above and clear of the sand.

Having described my invention, what I 60 claim and desire to secure by Letters-Patent, is:

1. The combination with the apertured anchor section of oil well tubing, of a sand shield open at its lower end and provided 65 with an aperture adjacent to said lower end and also provided with an upper reduced end portion snugly receiving and connected to the anchor section and adapted to maintain the major portion of the shield in spaced relation about the anchor section. 70

2. As a new article of manufacture, a sand shield for oil wells, of general tubular form, open at one end and apertured adjacent to said end and having at its opposite end a reduced tubular portion adapted to snugly receive and be connected to a well tube. 75

In testimony whereof I affix my signature.

FRED M. HARE.
